COMBINED BLADE DISPENSER AND RAZOR HOLDER

Filed March 24, 1937

FIG.1

FIG.2

INVENTOR:
RONALD KINNEAR
By ATTORNEY

UNITED STATES PATENT OFFICE

105,218

DESIGN FOR A COMBINED BLADE DISPENSER AND RAZOR HOLDER

Ronald Kinnear, Albany, N. Y., assignor to Niagara Insul-Bake Specialty Co., Inc., Albany, N. Y., a corporation of New York

Application April 24, 1937, Serial No. 68,963

Term of patent 7 years

To all whom it may concern:

Be it known that I, Ronald Kinnear, a citizen of the United States, residing at Albany, county of Albany, and State of New York, have invented a new, original, and ornamental Design for a Combined Blade Dispenser and Razor Holder, of which the following is a specification, reference being had to the accompanying drawing, forming a part thereof, in which—

Fig. 1 is a perspective view of a combined blade dispenser and razor holder, showing my new design; and

Fig. 2 is a front elevation thereof.

I claim:

The ornamental design for a combined blade dispenser and razor holder, as shown.

RONALD KINNEAR.
